UNITED STATES PATENT OFFICE

MILLARD S. BANKS, OF NEW YORK, N. Y.

DEVICE FOR USE IN BLOWING SMOKE RINGS

Application filed November 24, 1931. Serial No. 577,087.

This invention relates to improvements in devices for use in blowing smoke rings.

Devices of this kind have been provided comprising a tubular member having therein 5 means of one sort or another forming an obstruction extending inwardly from the wall of the member so as to provide a restricted central opening through which the smoke passes when blown into the device. Such devices, however, have only been partially successful.

An object of the present invention is to provide an improved device of this kind in which the middle portion of the tubular member is obstructed in a manner to cause the smoke blown into the device to be intercepted and guided or diverted to and against the inner wall thereof so that it can travel along the wall, and, by the resulting frictional engagement be caused to remain more or less in contact therewith in its passage through the device, and leave the device in the form of rings; also to provide a device of this character which is simple and efficient in use and with which smoke rings may be readily formed with the minimum practice and mouth control.

In devices of this kind heretofore provided, the tubular member has been rigidly constructed and was intended to permanently retain its form, so that such devices were relatively bulky and inconvenient to pack and transport, with resulting increase in cost to the purchaser.

A further object of the invention is to provide a device of this character which, while being practical and efficient in use, is readily collapsible into a substantially flat object so that it may be cheaply manufactured and can be inserted in an ordinary envelope and mailed as an advertising device or novelty, or can be inserted into a package of cigars or cigarettes without a material increase in the size or weight thereof.

Various other objects and advantages will be apparent from the following description of an embodiment of the invention, and the novel features thereof will be particularly pointed out in connection with the claims appended.

Fig. 1 is a perspective view of an embodiment of my improved device for use in blowing smoke rings, showing the same in condition for use.

Fig. 2 is a similar view showing the device 55 collapsed.

Fig. 3 is a fragmentary longitudinal section, on an enlarged scale of a portion of the collapsed device.

Fig. 4 is a similar view of the same portion of the device taken on line 4—4 of Fig. 3.

Figs. 5 and 6 are corresponding figures of the device when expanded, taken on lines 5—5 and 6—6 respectively of Fig. 7.

Fig. 7 is a transverse section of the device 65 on line 7—7, Fig. 6, in condition for use.

Fig. 8 is a fragmentary longitudinal section thereof, approximately on the line 8—8 of Fig. 7.

Fig. 9 is a perspective view of the baffle or 70 smoke diverting element of the device, detached.

In the illustrated embodiment of my invention, my improved device for use in blowing smoke rings comprises an elongate tubular 75 member 10 of cylindrical or other cross section having a smoke inlet end 11 and a discharge end 12. If desired, the inlet end 11 may be formed as shown in Figs. 1 and 5 so as to more readily fit the lips of the user.

In accordance with this invention, there is arranged within the tubular member 10, a baffle or element which is constructed so as to obstruct the middle portion of the member 80 while permitting the smoke to pass said element next to the inner surface 14 of said tube. Said baffle or element is also preferably constructed so as to provide a tapered or wedge-like surface directed towards the mouth or inlet end 11 of the device to thereby divert and 85 guide the smoke gradually towards the wall of the member 10 in a manner to prevent back currents or eddying of the smoke in such movement, and to concentrate the smoke 90 against said wall. Any suitable means may be provided for this purpose.

For example, in the embodiment of the invention illustrated, there is shown a baffle or element 20 having two oppositely inclined or bevelled faces or parts 21 which terminate 100

or meet to form an edge 22 approximately in an axial plane of the tubular member 10 so as to form a wedge-like or tapered obstruction preferably facing toward the mouth or 5 inlet end 11. The baffle 20 is preferably arranged near said inlet end 11. The baffle may face in the opposite direction if desired.

The faces 21 of the baffle 20 may be of substantially triangular shape having the 10 edge 22 as a common base and their side edges 24 extending rearwardly and disposed in spaced relation to the inner wall 14 of the tubular member 10. There is thus provided a series of spaces or openings 25 between said 15 baffle 20 and said inner wall 14.

In the illustrated construction, the edge 22 of the baffle or element 20 is preferably of a length substantially equal to, or only slightly less than, the inside diameter of the 20 tubular member 10, and the two edges 24 of each of the faces 21 thereof terminate at their rear ends in small tabs or attaching portions 26 by which the baffle 20 may be permanently attached to the inner wall 14 of the 25 member 10. The baffle or element 20 may be otherwise constructed to provide the tapered form and the marginal spaces for affording passage of the smoke next to the walls of the member 10, and the element 20 may be secured or supported in the member 10 in any 30 other suitable manner.

In the use of the device, the end 11 is placed in the mouth against the lips of the user and smoke is blown lengthwise through and out 35 of the member 10. As the smoke impinges upon the baffle 20, it is guided or diverted by the tapered faces 21 thereof into substantially wedge-shaped formations as the smoke moves towards the openings 25, where the smoke 40 is concentrated against the annular inner wall 14. As a consequence, all of the smoke passes through the openings 25 in a condensed form and continues toward the outlet end 12 in a substantially cylindrical 45 formation. Since the particles of smoke nearest to the inner surface of the tubular member tend to flow more slowly because of surface friction, it will be obvious that if smoke is blown into the device in puffs, rings 50 will be formed as the smoke leaves the end 12 of the tubular member. By causing the smoke to follow the wall of the tubular member by means of the baffle, the formation of such rings is facilitated. Such result will be 55 readily obtained by slight practice and the minimum of mouth control.

The device for use in emitting smoke rings as herein described may be formed of any suitable material, but is preferably made of 60 some durable and inexpensive flexible material such as stout, tough paper or material of similar character which, in addition to its low cost, will permit the device to be collapsed.

65 In order to permit the device to be col-

lapsed, the tubular member 10 is provided with longitudinal creases 30 or other analogous formations at diametrically opposite sides thereof, and the baffle 20 is likewise formed of a portion of similar material bent 70 to the shape shown, for example, in Figs. 5 and 9, the edge 22 being formed by a crease or fold which extends in the plane of the creases 30 of the tubular member 10. The baffle 20 is also provided with creases, folds 75 or other hinge-like formations 31 between the portions forming the faces 21 and the tabs or attaching members 26. It will be readily seen that the device can be collapsed into a substantially flat object or member, by exerting a slight pressure thereagainst in a direction substantially perpendicular to a plane passing through the creases 30, whereupon the tubular member 10 will take the form shown in Figs. 2-4, and the baffle 20 therein 80 will collapse at the same time along the edge 22 and the edges 31 so as to fold flat within the member 10 between the opposed, flattened halves thereof.

To place the device in condition for use, it 90 is only necessary to exert a slight pressure upon the tubular member 10 in the region of the creases 30 whereupon it and the baffle 20 therein will assume an expanded condition ready for use, and can be retained in this 95 form as long as this slight pressure is maintained.

When released, the natural elasticity or springiness of the material will, due to the 100 creases 30, cause the device to partially collapse, so that if inserted into an envelope or a package, or is placed in a pocket, the complete collapse of the device is readily effected.

I claim as my invention:

1. A device for use in blowing smoke rings comprising a tubular member through which the smoke is blown lengthwise, and a transverse baffle composed of a single part arranged therein and which is immovable in use relatively to said tubular member and which forms an obstruction in the middle portion of said member and permits the passage of smoke past said obstruction only adjacent the wall of said member. 105

2. A device for use in blowing smoke rings comprising a tubular member through which the smoke is blown lengthwise, and a transverse baffle arranged therein which obstructs the middle portion of said member and has a relatively small attaching portion by which it is secured to the wall of said member so as to provide an opening next to said wall for the escape of smoke past said baffle. 110

3. A device for use in blowing smoke rings comprising a tubular member through which the smoke is blown lengthwise, and a unitary transverse baffle arranged therein which has a middle portion disposed about the axis of said member to obstruct the middle portion thereof and has integral spaced portions ex- 115 120 125 130

tending to the wall of said member to maintain said baffle in relatively stationary relation to said tubular member and to provide openings between said wall and said middle portion of said baffle for the escape of smoke past the latter.

4. A device for use in blowing smoke rings comprising a tubular member through which the smoke is blown and which is collapsible lengthwise so as to be substantially flat, and a baffle within the same which obstructs the middle portion of said member when the latter is expanded and which is collapsible with said member.

15 5. A device for use in blowing smoke rings comprising a tubular member through which the smoke is blown, and which is formed of flexible material and is creased lengthwise at opposite sides so as to be capable of collapsing flatwise, and a transverse baffle within the same which is also formed of flexible material and obstructs the middle portion thereof when the same is expanded, and said baffle being creased so as to fold substantially flat with and by the collapse of said member.

20 6. A device for use in blowing smoke rings, comprising a tubular member through which the smoke is blown from one end to the other, and a baffle including a part spaced from the wall of said member to obstruct the middle portion thereof, said part of said baffle being tapered towards the inlet end of said member to deflect the smoke in wedge-like formation towards the space between said baffle and the wall of said member, whereby substantially all of the smoke will pass said baffle close to the wall of said tubular member.

25 7. A device for use in blowing smoke rings, comprising a tubular member through which the smoke is blown from one end to the other and which is formed of flexible material and is provided with longitudinal creases or the like at diametrically opposite sides to permit said member to be collapsed flatwise, and a baffle therein formed of flexible material folded between its ends to form a tapered obstruction in the middle of said tubular member and is spaced therefrom to provide 30 openings next the wall of said member through which the smoke is guided by said tapered obstruction, and said baffle also having folded attaching portions for securing said baffle to the inner wall of said member, and said baffle being collapsible along said 35 folds when said member is collapsed.

8. A device for blowing smoke rings comprising a tubular member through which the smoke is blown lengthwise, and means there- 40 in for obstructing the middle portion thereof and providing an opening about the same extending crosswise of said tubular member and through which opening smoke passes in a direction lengthwise of and next to the 45 wall of said device and continues in a length-

wise direction along said wall and leaves said device in the form of rings.

9. A device for blowing smoke rings comprising a tubular member through which the smoke is blown lengthwise, and means there- 50 in for obstructing the middle portion thereof to divert smoke blown into said device towards the wall of said member, said obstruction being spaced from and forming an opening extending crosswise between said wall 55 and said obstruction and through which opening the smoke blown into said device, including that which impinges upon and is diverted by said obstruction passes lengthwise of and next to said wall, and continues in 60 that direction along the wall of the device and leaves the latter in the form of rings.
